UNITED STATES PATENT OFFICE

168,258

VENETIAN BLIND SLAT

Jay Leon Friedman, Bronx, N. Y.

Application October 25, 1950, Serial No. 12,708

Term of patent 14 years

(Cl. D21—6)

To all whom it may concern:

Be it known that I, Jay Leon Friedman, a citizen of the United States of America, residing in the Borough of Bronx, city of New York, county of Bronx, and State of New York, have invented a new, original, and ornamental Design for a Venetian Blind Slat, of which the following is a specification, reference being had to the accompanying drawing, forming part hereof.

The Figure 1 is a perspective view of a Venetian blind slat showing my new design.

Figure 2 is an enlarged cross sectional view as seen from the plane 2—2 on Figure 1.

I claim:

The ornamental design for a Venetian blind slat, as shown.

JAY LEON FRIEDMAN.
